UNITED STATES PATENT OFFICE.

HOWARD B. MUNSON, OF CHICAGO, ILLINOIS.

HEEL-BLANK-CLAMPING DEVICE.

Application filed March 18, 1921. Serial No. 453,818.

To all whom it may concern:

Be it known that I, HOWARD B. MUNSON, a citizen of the United States, residing in the city of Chicago and State of Illinois, have 5 invented new and useful Improvements in Heel-Blank-Clamping Devices, of which the following is a specification.

This invention relates to shoe machinery and particularly to a self-contained portable 10 clamping device for clamping unattached heels while they are being trimmed by the rotary cutter of a heel trimming machine.

In one aspect the invention may be regarded an improvement of the clamping device 15 disclosed in my co-pending application Serial No. 347,327, filed the 26th day of December, 1919, for heel clamping device for use in trimming unattached heels.

A clamping device of this type embodies 20 in its construction a bracket with supporting means, for example, two plates to engage the upper and lower faces of the heel blank and this bracket is provided with means for moving one of these plates toward or from 25 the other to facilitate the introduction and removal of the heel blanks.

The general object of my invention is to provide simple and efficient means for supporting and guiding the movable heel plate 30 and to provide simple and efficient means for supporting and adjusting the bracket which carries the heel plate.

Further objects of the invention will appear hereinafter.

The invention consists in the novel features, and in the general combination of parts to be particularly described herein-after, all of which contribute to produce a simple and efficient heel-blank clamping device. A preferred embodiment of my invention will be particularly described in the following specification, while the broad scope of my invention will be pointed out in the appended claims.

45 In the drawing:

Figure 1 is a vertical section through the clamping device embodying my invention and showing a heel-blank clamped thereby;

Figure 2 is an end elevation of the clamping device with the heel-blank held in place;

Figure 3 is a cross section through the device taken on the line 3—3 of Figure 1; and

Figure 4 is a plan of the swivel plate which constitutes a feature of the invention.

55 Referring more particularly to the parts, 1^a represents the block or foot of a bracket 1

which is provided on its lower side with means for engaging the under face or bottom lift of a heel-blank 2. This means may be in the form of a heel plate 3, removably 60 and adjustably mounted on the under face of the bracket by means of screw bolts 4 and 5 which pass through slots 6. If desired heel plates such as the heel plate 3 of slightly different forms may be provided corresponding to different shapes or types of heels. The bracket 1 is formed above into a guide head 7 having a guide-way 8 in which there is received a slide 9. Any suitable means may be provided for preventing the 70 slide from rotating in the guide-way. I prefer simply to make the guide-way and slide of angular or square cross section. (See Figure 3). To the lower end of the slide a counter-plate 10 is rigidly secured by a removable screw 11, the head of the screw being received in a recess 12 in the curved under face of the counter-plate. When the heel-plate 3 is removed access may be had by a screwdriver to the slot in the head of the screw 11. 80 Associated with the slide 9 I provide a threaded stem having a thread of high pitch, co-operating with which I provide means for effecting the movement of the slide up or down in the guide-way 8. I prefer to 85 provide a threaded stem 13 extending upwardly from the upper end of the slide. The thread on this stem is of high pitch and for this reason is preferably a double thread. On the threaded stem I provide a nut 14 which 90 rigidly carries a swiveling collar 15 which rests against the upper face 16 of the guiding head 7. In order to hold the nut in place when it is being rotated I provide a swivel plate 17 (see Figure 4) which is preferably split on a diametrical line so as to form two sections which may be secured to the head 7 by means of counter-sunk screws 18.

The nut 14 may be rotated at will by 100 means of a removable wrench or lever 19 having a handle 20. A socket 21 is provided in the wrench lever near its middle point so as to facilitate the rapid application of the wrench, and its quick removal 105 from the nut when desired.

With this construction it will be evident that a relatively small angular rotation of the nut will impart a relatively great amount of movement to the counter-plate 10 110 away from the heel-plate 3, that is to say, a sufficient movement to enable the trimmed

heel to be removed and an untrimmed heel-blank to be quickly substituted and clamped in place.

1 provide means for adjusting and securing the bracket 1 in the foot 1^a. For this purpose the foot 1^a is provided with a socket 22 which opens away from the heel-plate 3, and this socket receives a tongue 23 extending downwardly at the lower end of the bracket. I provide means for adjusting the tongue and securing the same in the foot. For adjusting the bracket and securing the same against being pulled out by the clamping force I provide a threaded opening 24 in the lower end of the tongue which receives the upper end of the threaded bolt 5, and I provide the block with set screws 25 which seat against the side of the tongue so as to prevent the same from being forced downwardly. The lower end of the screw or bolt 5 is provided with a head 26 and a washer 27 which effectively resists any upward pull on the bracket which is occasioned by the tightening of the counter-plate 10 against the upper face of the heel-blank.

The block or foot 1^a of the bracket may be provided with a horizontal tongue or handle 28 which may be received in the socket 29 extending into a plate 30 from a vertical face 31, and this plate may be secured on the upper face of a table 32 or work bench.

It will be evident that by means of the screw 5 and set screws 25 the bracket 1 may be adjusted up or down so as to hold the counter-plate 10 at any pre-determined distance from the heel-plate 3.

What I claim is:

1. In a self-contained portable heel-blank clamping device, the combination of a bracket having relatively fixed means for engaging the bottom lift of the heel-blank, said bracket having a guiding head, a slide mounted to move on said guiding head and held thereby against rotation, a counter-plate carried by said slide for engaging the upper face of a heel-blank, a stem having a high-pitch thread associated with said slide, and means actuated at will and including a part engaging and co-operating with the threaded stem to move the slide up or down in the guide-way to effect the clamping and release of a heel-blank.

2. In a self-contained portable heel-blank clamping device, the combination of a bracket 55 having relatively fixed means for engaging the bottom lift of the heel-blank, said bracket having a guiding head, a slide mounted to move in said guiding head and held thereby against rotation, a counter-plate carried by said slide for engaging the upper face of a heel-blank, a threaded stem carried by the slide, a nut received on the threaded stem, means for holding said nut in place on the bracket so as to permit a 60 swiveling movement of the nut, and an operating lever for engaging the nut to rotate the same at will to clamp or release the heel, and constructed to be removable at will to permit the clamped heel to be applied to a 65 cutter.

3. In a self-contained portable heel-blank clamping device, the combination of a bracket having relatively fixed means for 70 engaging the bottom lift of the heel-blank, 75 said bracket having a guiding head, a slide mounted to move in said guiding head and held thereby against rotation, a counter-plate carried by said slide for engaging the upper face of a heel-blank, a stem having a high-pitch thread, carried by the slide, a nut on the outer face of the guiding head, a 80 swiveling collar rigidly carried by the nut, a plate secured on the guiding head and engaging the swiveling collar to hold the nut 85 in place, and means for rotating the nut to move the counter-plate to clamp or release a heel-blank.

4. In a heel-blank clamping device, the combination of a block, a heel-plate carried 90 on the under side thereof, said block having a socket opening away from the heel-plate, a bracket having a tongue lying in said socket, means for adjusting and securing said tongue in the socket, said bracket having a guiding head with a guide-way therein, a slide movable in said guide-way and held against rotation thereby, means mounted on the bracket for moving the slide toward or from the heel-plate, and a counter-plate carried by the slide and co-operating 95 with the heel-plate to clamp the heel-blank.

In testimony whereof, I have hereunto set my hand,

HOWARD B. MUNSON.
